UNITED STATES PATENT OFFICE.

JOHN W. BLIZNIK, OF DETROIT, MICHIGAN.

FOOT-OPERATED SWITCH-THROWING MECHANISM.

1,426,542.

Specification of Letters Patent. Patented Aug. 22, 1922.

Application filed April 3, 1922. Serial No. 549,052.

To all whom it may concern:

Be it known that I, JOHN W. BLIZNIK, a citizen of the United States, residing at Detroit, in the county of Wayne, and State of Michigan, have invented certain new and useful Improvements in Foot-Operated Switch-Throwing Mechanisms, of which the following is a specification, reference being had to the accompanying drawings.

It is the purpose of the present invention to provide a mechanism of this character, wherein a bar or member is mounted in the housing for reciprocating movements, with compound tensioning means operatively connecting with the bar for holding it at the limit of its movements in either direction, thereby holding the switch point open or closed, in combination with means, preferably foot actuated, and operatively connected with the reciprocating bar for moving the same, so that the switch point may be opened or closed.

It is to be understood that the particulars herein given are in no way limitative and that while still keeping within the scope of the invention, any desired modifications of detail and desired proportions may be made in the apparatus according to circumstances.

The invention comprises further features and combination of parts, as will be herein-after set forth, shown in the drawings and claimed.

In the drawings:—

Figure 1 is a plan view of a railway switch, showing the improved foot operated mechanism connected to the switch point, and constructed in accordance with the invention;

Figure 2 is an enlarged plan view of the housing with its top plate removed, showing the parts of said mechanism as having been actuated and the switch points opened;

Figure 3 is a sectional view on line 3—3 of Figure 2, taken at a point through the reciprocating bar, and showing the switch points closed;

Figure 4 is a sectional view on line 4—4 of Figure 2, transversely of the reciprocating bar, and illustrating the compound tensioning means;

Figure 5 is an enlarged detail perspective view of the foot actuated lever and its connections with an oscillatory member, which in turn operates with a reciprocating bar;

Figure 6 is a detail view of the connection with one of the foot pedals. Referring to the drawings, 1 and 2 designate the main rails, and 3 and 4 siding rails, whereas 5 and 6 denote the switch points.

A bar 7 connects the two switch points 5 and 6, and is guided below the rails, and is pivotally connected at 8 to a reciprocating bar 9, which is mounted for reciprocating movements in a housing 10 mounted upon the ties to one side of the main rail 2. This housing is constructed of any suitable material, preferably metal, and is provided with a cover 11, which is bolted in place as shown at 12.

The bar 9 has one end guided in an opening 13 in one wall of the housing, and a slot 14 adjacent its other end. Passing through the slot 14 is an upstanding pivot or fulcrum pin 15, which is mounted on the bottom of the housing. By means of the fulcrum or pin 15 and the slot 14, the reciprocating bar 9 is guided in its movements in one direction or the other.

Approximately the central portion of the bar 9 has an enlargement 16, in recesses 17 of which rods 18 are pivotally connected at 19. These rods 18 are guided in openings 20 of webs or walls 21, which are integrally connected with the housing. Washers or plates 22 are mounted on the outer end portions of the rods 18, and between these washers or plates 22 and collars 23 (which are fixed at 24 to the inner ends of the rods) are expansion coil springs 25. While the rods 18 have slight reciprocating movements in the guide openings 20, they also slightly oscillate due to the reciprocating movements of the bar 9. When the bar 9 has been moved and the switch points 5 and 6 are open, to cause a train to take the siding, the springs 25 are slightly expanded on one side of the line $a-a$, passing through the guide openings 20, and in this case the adjacent ends of the rods 18 have been moved closer to the switch points.

When the bar 9 has been moved in the opposite direction, namely moving the switch points 5 and 6 to their closed positions, in order that a train may continue on the main rails, the springs 25 are expanded on the opposite side of the line $a-a$ passing through the guide openings 20. In this case the adjacent pivoted ends of the rods 18

have been moved a greater distance from said switch points.

Mounted for oscillatory movement upon the fulcrum or pivot pin 15 is an oscillatory bar 26, to the ends of which links 27 are pivotally connected. These links are in turn pivoted to links 28, which in turn are pivoted at 29 to the arms 30 of a pair of bell crank levers 31.

10 A second oscillatory bar 32 is fulcrumed at 33 on a standard 34, which rises from the bottom of the housing. The bar 32 is provided with suitable foot pedals 35, either one of which may be engaged by the foot of 15 an operator, for oscillating the bar 32. Pivotally depending at 36 from the bar 32 are links 37, which are pivoted at 38 to the arms 39 of said bell crank levers 31.

Pivoted at 40 to one end of the oscillatory 20 bar 26 is a link 41, which in turn is pivoted at 42 to the reciprocating bar 9.

Obviously when pressure is applied upon one of the foot pedals 35, oscillating the bar 32, one or the other of said bell crank levers 25 31 is oscillated, which in turn oscillates the bar 26, thereby reciprocating the bar. Obviously the bar 9 will act to move the switch points either from an open position to closed 30 positions, or closed positions to open positions and vice versa.

The invention having been set forth, what is claimed is:—

1. In a switch throwing mechanism, a switch point, a housing, a bar mounted in 35 said housing for reciprocating movements therein and connected to said switch point, compound tensioning means cooperatively connecting with said bar and holding it at the limit of its movements in either direction, thereby holding the switch point open 40 or closed, said bar having a slot therein, an oscillating bar having its pivot passing through said slot to guide the reciprocating bar, and means operatively connecting with 45 each end of the oscillating bar, which in turn has means operatively connecting with the reciprocating bar for actuating the same to throw the switch point.

2. In a switch throwing mechanism, a 50 switch point, a housing, a bar mounted in said housing for reciprocating movements therein and connected to said switch point, compound tensioning means cooperatively connecting with said bar and holding it at the limit of its movements in either direction, thereby holding the switch point open 55 or closed, an oscillatory member, said reciprocating bar having operative guiding connections with the fulcrum of the oscillatory member, and means operatively connecting with each end of the oscillatory member which in turn has means operative-

ly connecting with said reciprocating bar for actuating the same to throw the switch point.

3. In a switch throwing mechanism, a switch point, a housing, a bar mounted in 65 said housing for reciprocating movements therein, and connected to said switch point, a spring tensioned means on each side of said bar and connected thereto at right angles therefrom, and adapted to expand on opposite sides of a dead center passing at right angles through the bar for holding it at the limit of its movement in either direction, thereby holding the switch point open or closed, said bar having a slot therein, an oscillatory member having its pivot passing through said slot to guide the reciprocating bar, and means operatively connecting each 75 end of the oscillating bar, which in turn has means operatively connecting with the reciprocating bar for actuating the same to throw the switch point.

4. In a switch throwing mechanism, a 85 switch point, a housing, a bar mounted in said housing for reciprocating movements therein, and connected to said switch point, a spring tensioned means on each side of 90 said bar and connected thereto at right angles therefrom, and adapted to expand on opposite sides of a dead center passing at right angles through the bar for holding it at the limit of its movement in either direction, thereby holding the switch point open 95 or closed, an oscillatory member, said reciprocating bar having operative guiding connections with the fulcrum of the oscillatory member, and means operatively connecting with each end of the oscillatory 100 member, which in turn has means operatively connecting with said reciprocating bar for actuating the same to throw the switch point.

5. In a switch throwing mechanism, a 105 switch point, a housing, an element mounted in said housing for reciprocating movement therein and connected to said switch point, compound tensioning means cooperatively connecting with said element and holding it 110 at the limit of its movement in either direction, thereby holding the switch point open or closed, an oscillatory device having means operatively engaging through said element for guiding the same, and means operatively 115 connecting with each end of said oscillatory device, which in turn has means operatively connecting with the reciprocating element for actuating the same, to throw the switch point.

In testimony whereof I hereunto affix my signature.

JOHN W. BLIZNIK.
